PRESSURE TANK

Sterling W. Alderfer, Akron, Ohio, assignor of
one-half to Edward D. Andrews, Akron, Ohio

Application October 19, 1942, Serial No. 462,628

4 Claims. (Cl. 220—3)

The present invention has for its object improving the construction of containers or tanks such as are used for holding gases under high compression. Tanks or containers of the type with which this invention deals are used for the holding and storage of gases which are used for inflating life rafts, life belts or collapsible boats such as form part of the equipment for landing parties. For such uses the gas employed is usually CO₂ under such high pressure that it is liquefied in the container.

The invention may be adapted to other and wider uses such, for example, as an oxygen tank used in airplanes or by parachutists who have to bail out at high altitudes. The invention may also be employed in other fields where it may be desirable to store or transport gases under high pressures.

The present invention is in the nature of an improvement upon the form of tank shown in my prior application Serial No. 452,979, filed July 30, 1942, to which reference is made.

Prior to the invention shown in my prior application, tanks which were universally employed were metal cylinders to which a charging and relief valve was affixed. Due to the enormous pressures which these tanks were required to withstand, the walls were made of a very high grade metal, usually reinforced by closely placed wrappings of piano wire or the like. This was an expensive construction and in addition such tanks were highly explosive and if punctured by a bullet or fractured in any other way the walls of the tank would shatter and fly apart, the flying fragments being dangerous to those in the vicinity. Frequently these tanks are worn by the aviators and the explosion of the tank may result in death or injury to the wearer. Other objections to the old form of tank were its cost and the difficulty in securing the required materials.

In the tank shown in my former application these objections and hazards were obviated but the capacity of the tank was somewhat restricted due to the fact that the entire volume was supplied by the coils of tubing. Also, the flexibility of the tank, while desirable in some cases, was found to be objectionable in others.

The present invention retains the safety and economy features of the earlier form of tank but is a rigid body and also has a greater volumetric capacity for a given bulk. The new form of tank is also easier to manufacture due to the fact that the interior of the tank is a rigid cylinder

or form about which the coils of pipe are formed and wrapped.

It will be understood that the specific embodiment of the invention shown herein need not necessarily be followed in all forms which may incorporate the new and novel features of the invention as set forth in the appended claims, and therefore changes and modifications may be made without departing from the invention.

10 In the drawing in which the best known and preferred embodiment of the invention is shown:

Fig. 1 is a plan view of a life raft or inflatable boat showing the manner in which the tank is employed when used in connection with this type of equipment.

Fig. 2 is a vertical section through the tank.

Fig. 3 is a section through the valve.

Fig. 4 is a section on the line 4—4 of Fig. 2.

Instead of employing a coil of tube or piping 20 as the storage space for the compressed gas as in my former construction, the volume is supplemented by a cylinder located within the coil of tubing, so that a greater total volume is provided in the same bulk. This permits an equivalent 25 body of compressed gas to be confined under reduced pressure or a greater volume at the same pressure as in my former tank construction. The property of non-shatterability is retained because the cross-sectional area of the outer coils of pipe 30 is relatively quite small and the bursting pressure in that portion of the tank is comparatively low, and if the tube is broken or punctured the gas will escape harmlessly. If the bullet penetrates to the inner tank the explosive force is reduced 35 and the outer coils of piping serve to hold the fragments from flying about.

The construction comprises an interior tank or container shown at 1 which is preferably made of a soft steel so that it will not shatter as is the case with the very hard steels which have been used in the single-chamber tanks which have preceded my tank constructions. The tank provides a core upon which the outer coils of tubing are wrapped. One end of the tank is provided with 40 a passage 2 through which the tank is filled and through which gas can escape when the valve 4 is opened. This valve is of the usual construction shown in Fig. 3 and is attached to a nipple 6 formed in the end of the tank body 1, and leads 45 by the extension 7 to the inflatable body 8 here shown as an inflatable landing boat or raft. The hand valve is indicated at 10.

If the tank is to be used as an oxygen tank the valve is attached to a breather pipe or the breather pipe and valve may be attached to the 50 55

free end of the tubing. For other installations these details may be varied as found necessary or desirable.

While the inner core or chamber is shown as a cylinder extending for the length of the tank these details may be varied. It is preferred, however, to form this portion of the tank as shown to constitute a form about which the outer enveloping coils of tubing may be wound. In winding the tubing about the core, it is desirable, to prevent undue flattening of the tube, to fill it with water or other fluid under pressure which is released after the winding operation is completed. The core serves to hold the entire tank body rigid which is advantageous for certain uses and installations. As is shown in the drawing, the winding of the tube causes it to flatten somewhat owing to the pressure exerted during the winding operation.

At one end of the tank the tubing 12 is connected to and in communication with the interior of the core by turning the end of the tubing into an aperture in the tank wall and permanently connecting it thereto, preferably by welding. The outer end of the tubing is closed off as at 14. The tubing may be of a soft steel, which is preferred, although copper tubing may be employed. The outer diameter of the tubing may be approximately $\frac{1}{4}$ inch, $\frac{3}{8}$, or even larger if desired, it being desirable to retain a relatively small across sectional area so as to reduce the pressure at any point in the tube wall. Because of the lower pressure the wall of the tubing may be quite thin, it having been found that a tubing $\frac{1}{4}$ " in diameter with a wall thickness of .025 inch is more than sufficient to hold gases under the very high pressures which are employed in tanks for the purposes set forth.

The tubing is wrapped about the core in any number of convolutions and layers. As shown three layers of tubing, each layer comprising closely packed convolutions, will give a total volumetric capacity in addition to the capacity of the core or central cylinder to hold a large volume of gas. After the tubing is completely wrapped it may be coated with a paint or shellac which will flow between the interstices of the structure. Also an outer covering or sac 15 may be provided.

It will be appreciated that the number of turns and layers of the coiled tubing and the size thereof and the size and shape of the core may be varied in accordance with the volumetric capacity desired and the pressures which are intended to be maintained. The advantages of the non-explosive tank have been retained but the interior hollow core has permitted a substantial increase in the capacity without losing that valuable feature of my prior invention. The outer wrappings of the metal tubing not only serve as a supplementary chamber but also reinforce the walls of the inner chamber, both by the inherent strength of the tube and by the pressure within the tube which offsets the outward pressure on the walls of the main chamber.

It has also developed that the tank shown herein has especial advantages as a container for liquefied gases such, for example, as liquid carbon dioxide. In the ordinary bottle tanks of the prior art, the release of the gas by opening the valve will cause the contents of the bottle to freeze solid while a considerable amount of carbon dioxide is left in the tank. This is due to

the absorption of heat by the gas as it passes rapidly from the liquid to the gaseous state which congeals the unexpelled contents of the tank so that it is possible to secure only a partial evacuation of the tank. A wholly unexpected result occurs with a tank constituted as shown, for tanks of this design do not tend to freeze up but discharge the entire contents in gaseous, mist or snow form.

- 10 This result is due to the fact that the liquid gas within the exterior coils will volatilize first due to the exposed condition of the coil. The gas will flow from the tube through the liquid in the body of the tank and will keep it in a state 15 of violent agitation until all of the contents are discharged, which prevents the contents from freezing as a solid mass. Any liquid gas which is frozen will turn into a fine snow and will be carried out by the gas in tiny snow-like particles 20 and no solid freezing of the contents of the bottle will occur. This is an immense advantage over the older types of container, especially in filling life boats or rafts in which it is urgent that the full capacity of the tank be released immediately.
- 25 What is claimed is:
1. A portable container for holding liquefied gas under pressure, comprising a main container having a release valve for discharging the contents of the container, and an auxiliary container 30 for holding a portion of the gas, said auxiliary container being formed of a pipe of smaller diameter than the main container said pipe being sealed at one end and communicating at the other end with the interior of the main container and tightly wrapped in a series of closely adjacent coils about the exterior of the main container.
  2. A portable container for holding liquefied gas under pressure, comprising a main container 40 having a release valve for discharging the contents of the container, and a tube of relatively small cross section one end of which is passed through the wall of the main container and opening therein, the remainder of the tube being sealed throughout, the tube being coiled tightly around the exterior of the main container to surround and serve as a reinforcement for the main container and also as an auxiliary container for liquefied gas.
  3. A portable container for holding liquefied gas or the like, comprising a tank, a release valve for discharging the contents of the tank, and a length of tubing one end of which is secured in the wall of the tank, the tubing being wrapped 55 against the exterior of the tank in a plurality of convolutions, the tubing communicating with the interior of the tank and otherwise sealed throughout, said tubing thereby serving as an auxiliary container for a portion of the liquefied gas.
  4. A portable container for holding liquefied gas or the like, comprising a tank, a release valve for discharging the contents of the tank, and a length of tubing one end of which is secured in the wall 60 of the tank at a point remote from the release valve, the tubing being wrapped against the exterior of the tank in a plurality of convolutions, the tubing communicating with the interior of the tank at the point of securement and being otherwise sealed throughout and thereby serving as an auxiliary container for a portion of the liquefied gas.
